UNITED STATES PATENT OFFICE.

ABRAHAM EDWARDS, OF PHILADELPHIA, PENNSYLVANIA.

WATER-CLOSET.

SPECIFICATION forming part of Letters Patent No. 242,287, dated May 31, 1881.

Application filed February 19, 1881. (Model.)

To all whom it may concern:

Be it known that I, ABRAHAM EDWARDS, a citizen of the United States, residing at the city of Philadelphia, in the State of Pennsylvania, have invented certain new and useful Improvements in Water-Closets; and I do hereby declare the following to be a full, clear, and exact description of the same, reference being had to the accompanying drawings, forming part of this specification, wherein—

Figure 1 is a vertical longitudinal section, partly in elevation, of my improvements. Fig. 2 is a plan of the same. Fig. 3 is a detail elevation of devices for lifting the sealing-cap of the water-closet bowl; and Figs. 4 and 5 are detail elevations of the same, drawn to an enlarged scale, illustrating the different positions they occupy when the sealing-cap is down and up respectively.

My invention has for its object to provide a water-closet with means for effectually excluding the escape of noxious gases and effluvia, whether from sewers, waste-pipes, traps, or the bowl itself.

My invention consists in the combination, with a water-closet having a bowl provided with a trough for containing mercury or other liquid or packing at or upon its upper edge, or having a valve-seat in such location, of a cap or valve constructed so as to seal in such trough or form a tight joint on such seat, said cap or valve being constructed and combined with operating mechanism so as to be moved upwardly and laterally to uncover the bowl when access to the latter is required.

My invention further consists in certain details of construction and combination herein-after set forth.

Referring to the accompanying drawings, A represents the bowl of a water-closet, said bowl being formed with an annular or endless trough or channel, *a*, around its upper edge, designed for the reception of mercury or other fluid substance to form a seal or rubber ring, or other material to form a packing or elastic valve-seat.

B represents a cap, which fits over the top of the bowl A and has a continuous flange or rib, *b*, adapted and designed to enter the trough *a* and dip in the mercury or other fluid therein, or to press into the rubber or other packing

and form a seal or perfectly-tight joint, which will prevent the escape of gases or effluvia from the bowl or any of the conduits below the latter. Said bowl is designed to be uncovered by 55 a compound movement of the cap, the latter being lifted vertically to permit the flange *b* to clear the trough *a* and then swung laterally. Various mechanical appliances may be used for accomplishing said movement, and hence 60 I do not limit my invention to any one in particular. I have shown one, however, suitable for the purpose, which I shall now proceed to describe.

In the accompanying drawings, C represents 65 a casting, in the form of a bracket, secured by screws *c* to the side of the bowl A. Said bracket affords bearings at *c*' to a vertical shaft, D, and at *c*'' to a counter or horizontal shaft, E. At its upper end the shaft D is fastened 70 to the cap B, so that both said cap and shaft shall move together. At its lower end the shaft D has fastened to it an arm, D', carrying a toothed segment, *d*.

The shaft E has at one end a rock-arm or lever, *e*, and at its opposite end a toothed segment, *e*', which gears with the segment *d*, and communicates motion to the latter and to the shaft D when said shaft E is rocked. Said shaft E also carries a cam, *e*'', which may be 80 separate from the segment *e*', or integral with the latter, if desired. The shaft D is supported on the periphery of the cam *e*'', so that when the shaft E is rocked said shaft D will be caused to slide in its bearings *c*'. 85

F represents the hinged lid of the water-closet seat G, and *f* a rod attached thereto and forming a connection with the lever *e*.

The operation is as follows: Normally the lid F being down the cap B covers the bowl 90 A and forms a tight joint therewith, effectually preventing the escape of all gases or effluvia therefrom. When the lid F is raised the shaft E is caused to rock through the medium of the rod *f* and lever *e*. This causes the cam *e*'' to lift the shaft D, and with it the cap B. When the flange *b* of the latter has cleared the top of the bowl, or risen wholly out of the trough *a*, the segment *e*' comes into engagement with the segment *d*, producing a rotation of the shaft 95 D and causing the cap B to be swung clear off the bowl, leaving the latter completely uncov- 100

ered. This movement of the cap B is effected by simply lifting the hinged seat-lid F, the reverse movement or return of the cap B to its position as a cover to the bowl A being accomplished by closing or letting down said lid. To afford room for the cap to one side of the bowl within the closet-casing said bowl is designed to be of an oval or approximate shape and the cap of corresponding contour.

10 The hole or opening *g* in the casing-seat G should be of less diameter than the top of the bowl A, as shown, said seat thus forming a covering or shed for the mercury-trough when the cap is swung off said trough, thereby protecting the contents of the latter from contact with person or clothing, or from being fouled by accident or carelessness.

15 The bowl A may be enameled, or it may be cast with lugs *a'* to afford supports for a porcelain bowl to be fitted therein, if desired.

What I claim as my invention is—

1. The combination, with a water-closet bowl having on or around its upper edge a trough

for the reception of mercury or other fluid, or a packing to form a valve-seat, of a cap or 25 valve provided with a vertical spindle or axis of rotation, whereby it is designed and adapted to form a cover for said bowl, and to be removed therefrom by being lifted and swung, substantially as shown and described. 30

2. The combination, with a water-closet bowl having a fluid-trough or packing-receptacle on or around its upper edge, of a cap or cover for said bowl, having a flange orrib corresponding to the bowl-trough, and adapted and designed 35 to enter the same, and means, substantially as described, for moving said cap vertically and swinging it laterally, as and for the purpose set forth.

In testimony that I claim the foregoing I have 40 hereunto set my hand this 18th day of February, 1881.

ABRAHAM EDWARDS.
